CLAIM

We claim the ornamental design for a sensor bar for electronic game machine, as shown and described.

DESCRIPTION

FIG. 1 is a front, top and right perspective view of a sensor bar for electronic game machine showing our new design;

FIG. 2 is a rear, bottom and left perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof, a left side view being a mirror image thereof;

FIG. 8 is a perspective view thereof, with the sensor bar shown in its use and located on the top of a television monitor; and,

FIG. 9 is a perspective view thereof, with the sensor bar shown in its alternative use and located in front of a television monitor.

The broken lines showing of television and cable are for illustrative purpose only and form no part of the claimed design.
